ABSTRACT OF THE DISCLOSURE

Jacks mounted on a needle cylinder are biased to move from an inoperative position to a working position guided by cam tracks to raise needles. Control members cooperate with the jacks and are individually controlled by a program controlled electromagnet and by cams to move selected jacks to the inoperative position.

The present invention relates to a selector apparatus for a circular knitting machine, and more particularly to selector apparatus for controlling selected cylinder needles of a circular knitting machine to assume at each feeding or knitting station, positions required by a desired pattern.

The selector apparatus of the invention is preferably provided in a circular knitting machine which has cylinder needles operated by jacks which are respectively aligned with the cylinder needles for moving the same.

The term "jack" is used herein to refer to any means by which the movement of needles of a knitting machine is influenced.

It is one object of the invention to provide a selector apparatus in a knitting machine by which selected jacks are actuated to cause desired needle movement.

Another object of the invention is to provide selector means by which the selection of needles can be carried out at a very high speed with great accuracy and without errors.

Another object of the invention is to provide a knitting machine with control elements actuated by electromagnetic selector means and being constructed in such a manner that a selection can be carried out within an extremely short time, while only a small magnetic force is required of the electromagnetic selector means.

With these objects in view, one embodiment of the invention is used in a circular knitting machine which includes a rotary needle cylinder, a cam box surrounding the needle cylinder and having at least one circumferential jack cam track including track portions rising and falling in axial direction; and a series of needles mounted on the needle cylinder for movement in axial direction. In accordance with the invention, a series of jacks registering with the needles is provided. Each jack is mounted on the needle cylinder for movement in axial direction, and also for movement in radial direction between an inoperative position and a working position engaging the jack cam track so as to be moved by the rising and falling track portions to and from an operative position for lifting the corresponding needles.

Selector means are mounted on the cam box for selectively placing jacks in the inoperative or working positions, respectively. Only those needles are lifted by the jacks, whose jacks are selected to be raised in the working position to the operative position engaging the respective needles.

Each jack has one end supported on the needle cylinder for angular movement between the inoperative and the working position, and has a butt located in the jack cam

track in the working position of the jack. A spring biases each jack to move outward in radial direction to the working position in which its butt is located in the jack cam track of the cam box. A series of control elements, 5 preferably straight resilient wires, is mounted on the needle cylinder located outward of the jacks. When a control element is actuated by the selector means, it is moved to an actuated position for moving the respective jack to the inoperative position. The control elements successively pass electromagnetic selector means during rotation of the needle cylinder, and also selector cam tracks. When a control element is attracted by the electromagnetic selector means, it moves along one selector track in a position spaced from the jack so that the same remains in the 10 working position into which it is urged by the biasing spring thereof. If a control element is not selected by the electromagnetic means, it passes upon another selector cam track which presses the resilient control element to the actuated position in which it engages the respective 15 jack and presses the same against the action of its biasing spring to an inoperative position in which its butt is located outside of the jack cam track.

In the preferred embodiment of the invention, the electromagnetic selector means has a selector core which is a permanent magnet. When a winding on the selector core is energized under control of pattern control means at 20 the moment in which it is passed by a control element, the magnetic field produced by the winding extinguishes or compensates the magnetic field produced by the permanent magnetism of the selector core, so that the respective control element is not held by the selector core, and released to move due to its resiliency toward the actuated position for displacing the respective jack.

Preferably, guide cam tracks are provided for guiding 25 the control elements successively into the proximity of the selector core, and a permanent magnet, which is not under the influence of a winding, follows the selector core for holding a selected and attracted control element until the same continues its movement on the selector cam track 30 which holds the respective control element in a position permitting the biasing spring of the corresponding jack to press the same into the working position. The rising and falling cam track portions of the jack cam track follow the selector magnet and the selector cam track means in 35 the direction of rotation of the needle cylinder so that the selected jacks are raised by the rising jack cam track portion to a position engaging the corresponding needles and placing the same on rising needle track portions on which the selected needles are displaced to assume at least the 40 tuck position.

Preferably, shifting means in the form of turnable cams mounted in the cam box are provided which have an operative position for raising selected needles from the tuck position to the highest knit position. The shifting means may be operated by pattern control means, or 45 manually set in the respective knitting and feeding station. A knitting machine to which the present invention is applied may, for example, have twenty four knitting and feeding stations.

The energization of the windings of the electromagnetic selector means at each knitting and feeding station takes place under the control of program control means which determine the knitting pattern.

In the preferred embodiment of the invention, a program tape is provided with as many program tracks as there are knitting stations and electromagnetic selector means in the machine. Each track consists of a sequence of transparent and opaque areas arranged in accordance 55 with the needle operations desired at the respective knitting station. A corresponding series of photodiodes receives the light passing through the pattern tracks, and 60

the impulses produced by the photo diodes are amplified and respectively supplied to the electromagnetic selector means at the knitting stations of the machine.

Preferably, synchronizing signals are produced by an impulse generator under the control of the needles, jacks, or grooves of the needle cylinder and assure that the electro-magnetic selector means are energized at the exact moment in which they are passed by a cylinder needle and the corresponding jack and control element.

In accordance with the invention, additional tracks are provided on the pattern tape. One additional track may be used for adjusting the position of the photoelectric sensing means if there is a phase difference between the sensed areas of the pattern tracks, and the passage of cylinder needles past the electromagnetic selector means. Another additional track is preferably entirely transparent, and is sensed to indicate whether the transparent areas of all tracks are sufficiently light permeable to assure proper operation of the photoelectric sensing means. If, for example, the areas have darkened, the voltage of the source of light scanning the pattern tracks is increased so that the lamp provides light of greater intensity, and the photo diodes receive the same amount of light irrespective of the condition of the program tape.

Some of the elements in the new combination of the present invention, are disclosed in the U.S. Patents No. 3,313,129, No. 3,365,916 and No. 3,292,393.

In the preferred embodiment of the invention, a cylindrical lens transports the program tape, and at the same time is part of a lens system by which a narrow line of light is focused by the cylindrical lens onto the program tape. In order to eliminate a phase difference between the tracks of the program tape and the position of the jack controlling elements when passing the electromagnetic selector means, the photo diodes are turned by a motor about the axis of the cylindrical lens an angle depending on the phase difference which is determined by a phase comparison device to which synchronizing impulses produced by the needle cylinder, and control impulses produced by an additional track on the pattern tape are supplied. The transparent areas of the additional track are uniformly spaced, for example, a transparent area may be provided for every second pattern track area so that a control impulse is supplied to the phase comparison device for every two synchronizing impulses.

The same elimination of a phase difference can be obtained by interrupting the transmission between the needle cylinder and the transporting means of the program tape. For example, two shafts respectively connected with the needle cylinder and with transporting means for the program tape carry spur gears having opposite helical teeth meshing with a helical spur gear fixedly secured to a common shaft which is axially shiftable and connected by a reduction transmission to a motor. The motor is controlled by a voltage produced by a phase comparison device responding to control signals produced by a photo diode sensing an additional control track on the pattern tape, and by the synchronizing impulses derived from the needle cylinder to shift the intermediate shaft and to turn the helical gear on the shaft of the transporting means.

By eliminating the phase difference, different pattern tapes can be used on which the transparent and opaque areas are displaced slightly different distances in relation to the transporting perforations.

If the machine is first controlled by a pattern tape to produce a certain pattern, and the pattern tape is replaced by another to produce a different knitting pattern, the control impulses produced by the pattern tracks of the new tape may be phase displaced in relation to the synchronizing impulses produced by an impulse generator under control of the needle cylinder, so that the synchronizing impulses do not coincide at all with the impulses produced by the photo diodes sensing the pattern track. As explained above, this phase difference can be eliminated by adjusting the position of the photo-

electric sensing means about the axis of the cylindrical transporting lens or by an automatically adjusted transmission between the needle cylinder and the transporting means for the pattern tape. In the latter case the actual displacement of the shaft carrying the two spur gears with helical teeth, effects adjustment and elimination of the phase difference.

Additional tracks on the pattern tape may also be used for other purposes, for example for producing a knitting pattern requiring operation of every second needle which may be accomplished by the control track having alternate transparent and opaque areas for controlling the comparison device.

The other additional control track, which is transparent throughout, serves, as explained above, for assuring that irrespective of the prevailing conditions, control signals of desired strength are produced by the photo diodes. The proper response of the photo diodes may be influenced by different factors. For instance, the sensitivity of the photo diodes at different temperatures of the machine may change, which would result in different responses after the machine has been stopped for some time and cooled off, and after the machine has been operated for some time. The scanning lamp may also lose its brightness after extended use. As noted above, the transparent areas of the pattern tape may become less light permeable as the tape ages. Finally, losses of light may occur if the program tape is slightly laterally displaced so that not the entire width of each pattern track is sensed by the photo diode.

By varying the light intensity of the scanning lamp, under the control of an additional control cam track, it is possible to obtain from the photo diodes control impulses of uniform strength.

A knitting machine according to the present invention comprises several novel features which cooperate to result in a Jacquard knitting machine which has unlimited possibilities of pattern variations, while the pattern can be selected and changed by the replacement of a program tape, preferably by means of a cartridge.

The following devices form part of the machine:

(1) An optical sensing device for a pattern tape including photoelectric devices, such as photo diodes.

(2) Control and regulating devices by which the impulses produced by the photo diodes are maintained at a uniform level, and amplifiers for the control impulses.

(3) Selector means including electromagnetic means and selector cams controlled by the control impulses received from the photo diodes and amplifiers so that the electromagnetic selector means are reliably controlled for producing the mechanical motions required for the selection.

(4) Radially movable jacks controlled by control elements actuated by the selector means.

(5) Shifting means in the needle cam tracks for selectively raising needles at the knitting stations to a higher position.

Due to this combination, it is possible to provide electric apparatus which is so small that all electric and electronic elements can be mounted within the base of a circular knitting machine which contains the drive means of the same, and also in other parts of the machine. The novel features of the invention permit the operation of the knitting machine at extremely high speed at which only very short time periods are available for the selection of needles in accordance with the knitting pattern.

A circular rib top knitting machine whose needle cylinder rotates at 18 revolutions per minute, and which has a needle circle diameter of 30 inches and 1,680 cylinder needles, affords the time of 1.8 milliseconds for the selection of a needle. Considering that a time interval must be provided between selections of successive needles, the sensing transmission of impulses and selection by the selector means must be carried out in less than 1 millisecond. Since the novel features of the invention result in a selection time of only 0.5 millisecond, it is possible to

increase the number of revolutions of the needle cylinders substantially over the usual 18 revolutions per minute.

Each program tape is located in a cartridge and has a length of about 150 meters. A program tape of this length is capable of producing 8 million control impulses. In order to control pattern wheels, for example, with a number of control impulses of this size in a conventional machine having twenty four knitting stations, twenty four pattern wheels each of which has a diameter of 150 meters would be required which, of course, is impractical. Even knitting machines which are controlled by electro-magnetic and mechanical selector means according to the prior art, are incapable of the storage and use of such an enormous number of control signals.

An advantage of the machine of the present invention is that no knowledge of the electronic apparatus is required of the operator, since the selection is automatic. The electronic devices are preferably constructed of transistors since the same permit a more compact construction and have greater mechanical resistance to shock. Parts of the photoelectric sensing device are disclosed in the U.S. Patent No. 3,317,735.

As explained above, jacks are selected by operation of the selector means. The selected jacks are controlled by a jack cam track to raise the corresponding needles onto a rising needle cam track portion which guides selected needles from the cast-off position to the tuck position, while non-selected needles continue their movement along a horizontal cam track in the cast-off position. A shifting cam is provided which can be placed in a position for forming a further rising track for the selected needles, so that the same are raised from the tuck position to the knit position. Following the shifting cam, the falling cam track of a stitch cam is located for returning the needles from the tuck or knit positions to the cast-off position. When the shifting cam is turned to an inoperative position, the respective needles are guided toward the falling cam track on the shifting cam in the tuck position without reaching the knit position.

This construction permits not only an unlimited selection of the jacks for moving the needles to the tuck position, but also a selection of the needles which are moved from the tuck position to the higher knit position. Shifting cams are provided at each knitting and feeding station of the circular knitting machine, and may be differently set at different knitting stations, entirely independent of the selection of the needles by the jacks under the control of the program controlled selector means.

In accordance with the invention, another shifting cam is provided leading the rising track portion of the needle cam by which the selected needles are raised to the tuck position. The second shifting cam, which leads the first-mentioned shifting cam in the direction of rotation of the needle cylinder, can be shifted to an operative position for guiding all needles out of their non-knit horizontal needle track portion onto the rising needle track portion, irrespective of the jack operation. This shifting cam can be turned to an inoperative position located below the needle cam track, and a corresponding cavity is provided in the cam plate which is attached to the cam box.

When the second shifting cam is operative, all needles are guided to the tuck position, and if the first-mentioned shifting cam is also operative, they are guided to the next position, while the selector means may be rendered inoperative.

The novel features which are considered as characteristic for the invention are set forth in particular in the appended claims. The invention itself, however, both as to its construction and its means of operation, together with additional objects and advantages thereof, will be best understood from the following description of specific embodiments when read in connection with the accompanying drawings, in which:

FIG. 1 is a fragmentary developed view illustrating 75

a segment of a cam box of a circular knitting machine provided with cam tracks according to the invention;

FIG. 2 is a fragmentary axial sectional view taken on line 2-2 in FIG. 1, and illustrating a selector apparatus according to the invention;

FIG. 3 is a fragmentary sectional view taken on line 3-3 in FIG. 1;

FIG. 4 is a fragmentary axial sectional view taken on line 4-4 in FIG. 1 and illustrating a jack in an inoperative position;

FIG. 5 is a fragmentary axial sectional view taken on line 4-4 in FIG. 1 and illustrating a jack in an operative position;

FIG. 6 is a fragmentary axial sectional view taken on lines 6-6 in FIG. 1 and FIG. 15 and illustrating a control element in an actuated position for moving the corresponding jack to the inoperative position;

FIG. 7 is a fragmentary axial sectional view taken on lines 7-7 in FIGS. 1 and 15 and illustrating a control element in a tensioned displaced position;

FIG. 8 is a fragmentary axial sectional view taken on lines 8-8 in FIGS. 1 and 15 and illustrating a control element attracted by electromagnet means and another control element released by the electromagnet means;

FIG. 9 is a fragmentary axial sectional view taken on lines 9-9 in FIG. 1 and FIG. 15, and illustrating a control element in the displaced tensioned position;

FIG. 10 is a fragmentary axial sectional view taken on lines 10-10 in FIGS. 1 and 15;

FIG. 11 is a fragmentary view taken on line 11-11 in FIG. 15, and illustrating electromagnetic selector means;

FIG. 12 is a fragmentary sectional view taken on line 12-12 in FIG. 11, as viewed from the right in the direction of the arrow 12 in FIG. 11;

FIG. 13 is a fragmentary sectional view taken on line 13-13 in FIG. 11, and on lines 8-8 in FIGS. 1 and 15;

FIG. 14 is a fragmentary sectional view taken on line 14-14 in FIG. 11;

FIG. 15 is a horizontal sectional view taken on line 15-15 in FIG. 1 and illustrating selector means according to the invention;

FIG. 16 is a diagram illustrating the electric circuit of pattern control apparatus by which the energization of electromagnetic selector means according to the invention is controlled by a program tape;

FIG. 16a is a fragmentary sectional view illustrating an electromagnetic sensing means controlled by the needle cylinder of the knitting machine;

FIGS. 16b and 16c are diagrams illustrating a circuit for producing rectangular synchronizing impulses;

FIG. 16d is a diagram illustrating an electric circuit for combining pattern representing impulses produced by photoelectric sensing means with synchronizing impulses shaped by the circuit of FIGS. 16b and 16c;

FIG. 17 is a side elevation illustrating a photoelectric sensing apparatus forming part of the pattern control apparatus of FIG. 16;

FIG. 18 is a plan view of the apparatus of FIG. 17;

FIG. 19 illustrates a detail of the apparatus of FIGS. 17 and 18 on an enlarged scale; and

FIG. 20 is a fragmentary view illustrating a section of a program tape used in the pattern control apparatus illustrated in FIG. 16; and

FIG. 21 is a fragmentary sectional view illustrating a device for adjusting the position of the program tape in relation to the position of the needle cylinder.

Referring now to the drawings, and more particularly to FIGS. 1 and 2, a needle cylinder 2 is rotatable about a vertical axis of rotation, not shown, and has circumferentially adjacent peripheral channels 18 extending parallel to each other in axial direction and being separated by walls 4 which are preferably inserted into corresponding grooves 4b of needle cylinder 2. Needles 1 are mounted for axial sliding movement in channels 18 and have butts 1' located and guided in a needle cam track 6

in an annular cam box 90 which surrounds needle cylinder 2. Cam box 90 is divided into as many sectors as there are knitting or feeding stations provided in the machine, and each sector has an upper part T' and a lower part T'' which abut each other in a common plane T extending perpendicular to the axis of the needle cylinder. The lower parts T'' are secured by screws 171 to a circular base 182, and the upper parts T' are secured to the respective lower parts by screws, not shown, which permit detachment of the upper part of each sector.

Cam plates are secured to the inner surface of each sector part and form circumferential cam tracks with slanted cam track portions rising and falling in axial direction.

The needle cam track 6 has a lower guide face which is formed by the upper edge of a cam plate 100 which is secured by screws 100'. The upper guide face of the needle cam track is partly formed by stitch cam plate 10 having a slanted surface 10', and by another cam plate 9 to which a further cam plate 17 is secured which has a projection forming a rising cam track 7', as best seen in FIG. 1 which shows one sector S of cam box 90.

A jack 3 is slidably mounted in each channel 18 of the needle cylinder 2. The term "jack" is used herein to define a control member which influences directly or indirectly movements of a needle. In the illustrated embodiment, a jack 3 registers with each cylinder needle 1. Each jack has a lower end portion 3a which is rounded off and slidably abuts a corresponding bearing seat 3b at the end of the respective channel 18. Consequently, each jack 3 is mounted for angular movement between a working position in which its butt 3' is located in a jack cam track 5, and an inoperative position shown in FIG. 4 in which the jack has turned about its lower end 3a against the action of a spring 19 which is secured to each jack, and has a curved portion abutting the bottom 18a of the respective channel 18. Each jack has a projection 3d which is located in close proximity of a resilient control element 21 which is shown to be a straight resilient wire secured to a ring 22 surrounding the needle cylinder and secured to the same by screws 23.

Biassing means 19 urge the jacks into the working position shown in FIG. 2, but when a control element 21 is turned to the position shown in FIG. 6, for example, it engages projection 3d and turns the respective jack in counterclockwise direction to an inoperative position in which butt 3' is located outside of jack cam track 5, and biassing spring 19 is resiliently deformed. As clearly shown in FIG. 2, each jack 3 is aligned with a corresponding needle 1 only in the working position.

Jack cam track 5 is located in the region of the dividing plane T, and has horizontal cam track portions 5h which are located in a plane perpendicular to the axis of the needle cylinder. A rising cam track portion 5', a falling cam track portion 5'', and a horizontal high cam track portion 5a are provided between the horizontal cam track portions 5h. When a jack 3 moving in the direction of the arrow P with the needle cylinder while being in the working position is raised by the rising cam track portion 5' to the operative position shown in FIG. 5, the upper end of the jack engages the corresponding needle and raises the same to the higher position shown in FIG. 3 whereupon the falling cam track portion 5'' lowers the jack again.

Selector means are provided in the region of cam 127 for placing selected jacks in the working position, and non-selected jacks in the inoperative position in which the respective butts are not located in the rising cam track portion 5', but slide on the outer surface of cam 20, as shown in FIG. 4 so that the respective needles are not engaged and raised by non-selected jacks.

The needle cam track 6 has a cam track 6i extending over the entire circumferential length of each cam box sector in a plane perpendicular to the axis of rotation of needle cylinder 2, so that needles whose butts remain on

track 6i, remain in the lowest position which corresponds to the cast off position, so that the respective needles cannot catch a thread or form a loop. At a point 7, a rising cam track 7' branches off, and needles whose butts are controlled by track portion 7' are raised to the tuck position. If a shifting cam 11 is in the illustrated position, the needle is further raised to the point 8 at the upper end of shifting cam 11 where the needle is in the knit position. A falling track portion 13 ending in a point 13', and another falling stitch cam portion 10' lower the needle to the cast off position in which the butts are again located on the horizontal track 6i.

Point 7 at which the rising track portion 7' starts in the direction P of needle movement and rotation of the needle cylinder, is located behind the upper end of the rising jack cam track portion 5'. Consequently, those jacks which are selected to be moved by cam track 5' in the working position to a higher operative position, engage the corresponding needles 1 before the butts of the same reach point 7, and raise the corresponding needles onto the rising needle track portion 7' for further movement to the tuck position. If shifting cam 11 is in the illustrated position, the respective selected needle is further raised to the knit position, but if shifting cam 11 is turned in counterclockwise direction about a pivot means 12 in the cam box, the respective needle remains in the tuck position and travels along a horizontal path toward stitch cam 10' by which it is lowered to the cast off position.

Shifting cam 11 cooperates with a locking means 14 which is turnable about its pivot 151. Locking means 14 is turnable to the illustrated locking position arresting shifting cam 11 in its operative position, but when locking means 14 is turned in counterclockwise direction to an inoperative position, shifting cam is lowered so that its cam face 11' is parallel to needle track 6i and located slightly above the same so as not to interfere with needle butts 1' traveling along track 6i.

As long as shifting cam 11 is in the illustrated operative position, all needles are raised to the knit position and then lowered by cam tracks 13 and 10' to the cast off position.

Those needles which are not raised by non-selected jacks which are in the inoperative position shown in FIG. 4, pass the sector in the cast off position while the butts thereof are guided along track 6i.

The position of shifting cam 11 can be selected, and may be different or the same in successive cam box sections corresponding to knitting or feeding stations. Shifting cams 11 may be manually set to selected positions at the various knitting stations of the machine, but it is also possible to control shifting cams 11 by pattern control means substantially as described in the U.S. Patent 3,186,192. The chain line 1a schematically indicates the path of movement of a needle which is raised to the knitting position, and the path of the upper end of a jack which is raised to the operative position is indicated by a chain line 3c.

Another shifting cam 15 is mounted for turning movement in the cam box and located in a recess in the outer face of cam plate 100. Shifting cam 15 cooperates with a turnable locking means 16, and can be turned to a position, not illustrated, in which shifting cam 15 forms a rising cam track connecting point 7 with the horizontal track 6i so that all needles are raised by shifting cam 15 to the rising track portion 7' and raised to the tuck position, or to the knit position depending on the position of shifting cam 11. As long as shifting cam 15 is in the operative position connecting track 6i with track 7', it is immaterial whether the corresponding jacks are in the inoperative or working position.

Shifting cam 15 is operated only if no selection of jacks is desired. As noted above, selector means which will be described hereinafter, place the jacks either in the inoperative position of FIG. 4, or in the working position of FIG. 5 so that selected needles are raised, while non

selected needles remain in the cast off position on cam track 6i. When the selector means are not operated, shifting cam 15 is set either to cause all needles to remain in the cast off position while passing through the respective knitting station, or all move to the tuck or knit position.

As noted above, each sector comprises a lower part T'' and an upper T', and when the upper part T' is detached from the lower part, the jacks and needles are accessible and can be observed and adjusted while the needle cylinder is slowly turned. While the detachable parts of each segment are shown to have cam tracks corresponding to one knitting or feeding station, it is possible to provide two or more raising and falling cam track portions in each sector, corresponding to two knitting stations in each sector.

As noted above, each jack 3 can be turned by resilient control element 21 in clockwise direction and against the action of its spring 19 from the working position shown in FIG. 2, for example, to the inoperative position shown in FIGS. 4 and 6 in which the respective butt 3' is not located in the jack cam track 5.

The selector means are located in the region of cam 127 between points h and a. The construction and operation of the selector means will be best understood with reference to FIG. 15, taken together with FIGS. 6 to 10 and FIGS. 11 to 14.

Every jack arriving at point h is in the working position with butt 3' located in jack cam track 5. The corresponding control element 21 is in its normal position in an axial plane passing through the axis of needle cylinder 2, and located between two round projections 4a, shown in FIG. 2. The lower portion of cam 127 has a guide cam 27 and a selector cam 28. Selector cam 28 has circumferentially extending selector cam track means including a first selector cam track 28b located radially outward, and a second selector cam track 28c located radially inward. A track portion 28d intersects with the first selector cam track 28b at an axially extending edge d. Guide cam 27 has a radially outward located guide track portion 27a rising in radially outward direction between points h and g, and the radially inwardly located guide track portion 27e extending between point e and f'. A radial shoulder connects points f and f'.

Control elements 21 moving in the direction of the arrow P in FIGS. 1 and 15 with the needle cylinder are first in the normal straight position shown in FIG. 2 since this position was restored in the preceding sector of the cam box. As best seen in FIG. 15, control elements 21 arriving at point h are guided by a guide face 27a toward an electromagnetic means 24, and more particularly toward its first core 24a, as best seen in FIGS. 15 and 9. As best seen in FIGS. 11 to 14, electromagnetic means 24 has a second core 24b which is longer in circumferential direction than core 24a. Core 24b is a permanent magnet, and preferably core 24a is also a permanent magnet having the same polarity. A winding 26 is mounted on core 24a and suppresses the magnetic field of core 24a, when energized.

The permanently magnetic cores 24a and 24b have pole shoes located between two outer pole shoes 24c of opposite polarity.

If winding 26 is not energized when a control element 21 is guided by guide track 27a into its proximity, the respective control element is attracted, and is moved by the needle cylinder in the direction of the arrow P onto the end face of core 24b on which it slides in tensioned condition until it passes beyond the same and resiliently drops on the selector track 28b on which it further moves beyond the point b and along an inwardly slanting track portion which permits the control element to return from its tensioned position to its normal position. Selected control elements in the tensioned position are bent as shown in FIGS. 9, 8, and 7. It will be understood that all control elements between the point g and the point b, which were attracted by core 24a, are in a radially out-

ward displaced bent and tensioned condition from which they return in the region of point a to the normal straight position in which one control element is shown in FIG. 5.

If winding 26 is energized in the moment in which a control element 21 is guided by guide track 27a into the proximity of the end face of core 24a, the tensioned bent control element is permitted by shoulder f, f' to return to its normal position. However, the resilient control element will swing beyond its normal position and be stopped by the track face 27e and then return to its normal position. The end e of track portion 27e leads edge d in a direction of movement P so that control elements in the position 21b are placed on the inwardly slanted selector track portion 28d and guided along the same to the position shown in FIG. 6 which is assumed beyond point c. Control elements 21c in this position are bent and tensioned in the opposite direction than the selected and attracted control elements 21a, and also return to the normal position after passing beyond the end point a of selector cam 28.

Control elements moving along selector track 28c between points c and a displace in the position of FIG. 6 the corresponding jacks 3 which are turned in counter-clockwise direction to the inoperative position shown in FIG. 6 in which butts 3' are located outside of jack cam track 5, so that the respective jacks are not raised by cam track portion 5', and cannot influence the corresponding needles to move out of needle track 6i onto the rising needle track portion 7'. Consequently, those needles which are associated with non-selected control elements 21c, remain on needle track 6i in the low cast off position, and do not participate in the knitting operation. On the other hand, selected jacks whose corresponding control elements 21 are held by selector tracks 28b, are held by the respective spring 19 in the working position, as shown in FIG. 7 so that the respective butts 3' engage the rising track portion 5' and are raised in the working position to the operative position shown in FIG. 5 engaging the corresponding selected needles 1 raising the same so that the respective needle butts 1' are placed on the rising cam track 7', instead of remaining on the low track 6i, whereby the respective needles are raised at least to the tuck position, and farther to the knit position if shifting cam 11 is in its operative position. Each selected needle is raised by the rising track portion 7' so high that it separates from the upper end of the corresponding jack, as shown in FIG. 3, although the same is raised to its operative position in which its lower end 3a is lifted above the seat 3b in the needle cylinder structure. During further turning of the needle cylinder, the needles are retracted to cast off position by falling cam track portions 13 and 10' until the position of FIG. 2 is assumed by the needles. The falling track portion 5'' of the jack cam track lowers the previously selected jacks until the same arrive on the horizontal track portion 5h and assume the position shown in FIG. 2. Those jacks which were not selected by electromagnetic means 24, and which were placed by selector track portion 28c in the position 21c shown in FIG. 6 travel along the horizontal path 3'' in the position of FIG. 4 until arriving at the horizontal track portion 5h. The corresponding needles are consequently not raised and their butts remain on needle track 6i in the cast off position, as shown in FIG. 2.

As shown in FIGS. 8, 9 and 10, the electromagnetic means 24 is mounted in a corresponding cutout or recess of each sector T'' of the cam box 90.

FIG. 11 shows that the gap between the end faces of cores 24a and 24b is narrower than the wire control elements 21 so that the control element in the position 21a can slide over the gap. The circumferential extension of core 24a is the same as the circumferential spacing between control elements 21 so that only one control element is attracted, or not attracted by core 24a when the coil is not energized, or energized, respectively, to ex-

tinguish the magnetic field produced by the permanent magnetic core 24a.

FIG. 12 shows core 24a energized by winding 26 so that the polarity of core 24a, which normally corresponds to a north pole, is reversed so that a control element 21 placed by guide track 28a in the displaced tensioned position 21a is not attracted, but released to assume the position 21b on guide track 27e. FIGS. 13 and 14 show positions in which control elements in the position 21a are held by the permanent magnetic core 24b sliding on the same until passing beyond it and dropping on selector track 28b to permit selected jacks to remain in the working position by the action of the respective biasing spring 19. The polarity of the cores is indicated by reference characters N for north pole and S for south pole.

From the above description of the selector means, it will become apparent that the same are provided for each knitting station or feeding station of the circular knitting machine. For example, a circular knitting machine may have twenty-four knitting and feeding stations, each of which is provided with a selector means including an electromagnetic means 24 with a winding 26, guide cam means 27, and selector cam means 28. In accordance with the invention, the energization and deenergization of windings 26, by which the selection of jacks and corresponding needles is determined, is controlled by pattern control means which cause energization and deenergization of the electromagnetic means 24 of each knitting and feeding station in a predetermined sequence.

In the preferred embodiment of the invention, pattern control means as shown in FIG. 16 are provided. A program tape 110 is guided by a roller 128a out of a cartridge 128 which includes a letoff roller and a take-off roller. The endless program tape 110 is guided over a cylindrical lens 101 which has sprockets 129 for engaging rows of perforations in tape 110 as schematically indicated by chain lines 110a in FIG. 20. A source of light 109, see also FIGS. 17 and 18 projects light through an aspherical condenser lens 126 and a plano-convex cylinder lens 127 into cylindrical lens 101 which focuses the parallel rays passing through lens 127 in a narrow line which extends perpendicular to the direction of movement of program tape 110, and to the tracks on the same, as described in the U.S. Patent No. 3,317,735.

Assuming that twenty four program tracks 110/1 to 110/24 are provided, as shown in FIG. 20, corresponding areas of the twenty four tracks located along a transverse line will be illuminated by lens 101, irrespective of the fact that lens 101 turns while transporting program tape 110.

Program tape 110 has at least two additional tracks 110/25 and 110/26 which serve to control auxiliary devices while the twenty four other tracks control the energization and deenergization of the twenty four electromagnetic means 24 which are respectively provided at the knitting stations of the machine.

A corresponding number, for example 26 light guiding rods 130 are placed with the thinner ends thereof along the illuminated line of the program tape, and guide the light, as shown in FIG. 19, toward a corresponding number of photo diodes 104 which produce an impulse when the respective track passing through the illuminated line as a light permeable area, and produces no impulse if the respective illuminated track area is opaque.

The program tape 110 may be a 35 mm. film provided with twenty six tracks including twenty four program tracks as explained above. If a film tape of greater width is selected, a greater number of tracks can be provided for knitting machines having a greater number of feeding and knitting stations. The white rectangles in each track of FIG. 20 represent light permeable areas, while the dark track portions of FIG. 20 indicate opaque areas of the film tape.

Each light permeable transparent area causes a control impulse of the respective photo diode 104, which is

used for controlling the energization of the corresponding electromagnetic means 24, a number of which are schematically illustrated in FIG. 16. If the outermost track 110/25 is used for controlling the knitted pattern, it influences every second needle. In the illustrated embodiment, however, track 110/25 is used to produce a synchronizing signal so that, if the program tape is exchanged for another tape representing a different pattern, minor differences in the position of the track area in relation to the transporting perforation 110a can be adjusted and eliminated.

In the tape illustrated in FIG. 20, the first seven tracks 110/18 to 110/24 control all needles in needle cylinder 2 while the needles pass from the eighteenth to the twenty fourth knitting station. The remaining seventeen tracks 110/1 to 110/17 have transparent and opaque areas in a predetermined sequence so that only selected needles 1 are influenced by the selector means and selected jacks, as explained above. In the event that more than one selector means is provided within a knitting station, a corresponding additional track must be provided for the respective knitting station. It is also possible to use one of the additional tracks 110/25 or 110/26 for this purpose, in addition to its normal function. FIG. 20 shows a program tape enlarged substantially in the ratio 2:1.

In the illustrated program tape 110, the additional track 110/26 is continuously transparent and has no opaque areas. This track is used for controlling the brightness of the source of light 109 at a desirable level of intensity.

30 The impulses produced by photo diodes 104 (1-24) are supplied to a corresponding electromagnetic means 24, but are first synchronized with the rotary needle cylinder 2 so as to assure that each electromagnetic means 24 is energized or deenergized at the exact moment in 35 which it is passed by a control element 21, and the corresponding jack and needle.

Assuming that a circular knitting machine has 1680 cylinder needles, and a cylinder diameter of 30 inches, a control element 21 will pass an electromagnetic means 40 24 within 0.5 to 1 millisecond, and within this time period, the above explained selection, or non-selection, of a corresponding control element must be completed. The same extremely short time period is available for the production of a control impulse by a photo diode 45 sensing an area of a program track on program tape 110. A synchronization of the control impulses produced by photo diodes 104 with the rotary movement of the needle cylinder is required. Synchronizing apparatus for this purpose is described in the U.S. Patent No. 3,313,129, and 50 the corresponding circuit is illustrated in FIG. 16.

55 The transporting lens 101 is driven from needle cylinder 2, as schematically indicated by the broken line 123. Any deviation from exact synchronism between the passage of track areas past sensing means 130, 104 and the passage of control element 21 past core 24a of the corresponding electromagnetic means must be corrected.

As best seen in FIG. 16a, an impulse generator 111, see FIGS. 16 and 16b, includes a magnet core 111a with a winding 111b, is placed in the proximity of the needle cylinder so that the magnetic field is influenced by the projecting walls 4 and channels 18 between the same to produce impulses which represent the time required for the passage of a control element 21. As schematically shown in FIG. 16, the impulses are supplied to a pulse shaper 112 which supplies rectangular impulses 117 to an AND-gate 113 which also receives impulses from one of the photo diodes 104 through a line 124. Impulses 118 are in a sequence determined by the respective program track. Only one line 124 is shown, but twenty four lines 124 have to be provided for the twenty four photo diodes sensing twenty four program tracks of program tape 110. The synchronizing impulses 117, and the program impulses 118 are combined in the AND-gate 113 to form rectangular impulses 119 in a sequence determined by the program represented by the respective program

track. Impulses 119 are exactly synchronized with the passage of control elements 21 past the respective electromagnetic means 24 so that the latter is energized or deenergized whenever passed by a control element 21 in accordance with the program represented by the respective program track on program tape 110. An amplifier 114 amplifies the impulses by which electromagnetic means 24 is energized. The circuit of the impulse generator 111 and pulse shaper 112 is shown in greater detail in FIG. 16b. An oscillator O produces oscillations schematically indicated at O' which are supplied to a bridge circuit B one branch of which is connected with the winding 11b so that oscillations O' are modulated due to the changes of the magnetic field of electromagnetic means 111a, 111b caused by the ridges and channels of the needle cylinder and influencing the equilibrium of the bridge circuit. In the circuit 112a, the modulated voltage B' is amplified by amplifier A to shape A', rectified and demodulated by rectifier R and demodulator D to assume shapes R' and D', supplied to a Schmitt trigger T, a differentiator Di and to an amplifier AA while successively assuming the shapes R', D', T', Di' and 117. The output of amplifier AA is connected with the input of the circuit 112b shown in FIG. 16c so that the rectangular impulses first enter the monostable flip-flop device F and then the amplifier Am.

The circuit of the AND-gate 113 and amplifier 114 is shown in FIG. 16d. A preamplifier P is combined with the AND-gate 113 and has a first input terminal receiving impulses 118 from photodiode 104/24, and a second terminal receiving synchronizing impulses 117 from line 102. The preamplifier is adjustable to respond to different voltages. The effect of an AND-gate is obtained when transistor OC 430 bypasses the feed back path of amplifier BSY 76 and OC 467, and only opens when a synchronizing impulse closes transistor OC 430. The rectangular impulses 119 which are spaced in accordance with impulses 118 and the controlling pattern track 25, are amplified in amplifier 114, to the shape 119a and control electromagnets 24.

Pulse shaper 112 is not only connected by line 102 to the amplifier P and AND-gate 113, but is also connected by a line 115 to a phase comparison device 116 to which also controlled impulses 125 produced by a photo diode 104/25 sensing track 110/25 are supplied. As noted above, track 110/25 has uniformly spaced light permeable areas spaced twice the distance of the pattern areas of the other program tracks. Therefore, an impulse 125 reaches phase comparison device 116 for every two impulses 117a. When a phase difference occurs between impulses 125 and 117a, a voltage is produced by phase comparison device 116 which is amplified by amplifier 120 and supplied to a motor 105 which it turned when there is a phase difference, and at a standstill when there is no phase difference.

Motor 105 has a pinion meshing with a circular gear segment 106 whose center coincides with the center of transporting lens 101, and which is fixed to a support 107 on which the photo sensing device is mounted.

In the event that a program tape is substituted for another program tape by changing cartridge 128, and assuming that in the new program tape the position of the areas of the pattern tracks to the transporting perforations 110a is different than in the previous tape, then the impulses 125 produced by the control track 110/25 are not exactly in phase with the synchronizing impulses 117a, and a voltage and current is produced and supplied to motor 105 which adjusts the position of the photo sensing device in relation to the program tape until exact synchronization and phase coincidence is obtained. Another device for adjusting the position of the program tape in relation to the position of the needle cylinder is illustrated in FIG. 21. The shaft 123 which in FIG. 16 is schematically indicated by a broken line to establish a driving connection between the needle cylinder and the cylindrical lens and transporting means 101 of the pro-

gram tape 110 has in the construction of FIG. 21 two separate portions 123a and 123b respectively connected with the needle cylinder and with the transporting lens means 101. Shaft portions 123a and 123b are mounted in bearing means 155 carried by a frame part 156 of the machine, and also including a bearing for a shaft 154, which has annular rack teeth 154a and is further supported in a bearing 157.

Shafts 123a, 154, and 123b carry helical gears 150, 153, 151 meshing with each other. A gear 158 meshes with rack portion 154a and is fixed on the shaft of motor 105 which is driven by a voltage received from amplifier 120 of the phase comparison device 116. When a phase lag occurs between the needle cylinder and the control track on the program tape, motor 105 turns in one or the other direction so that shaft 154 with the intermediate gear 153 are displaced in axial direction whereby gear 150 is turned in one or the other direction until the program tape and the areas on the tracks of the same are in the correct position in relation to the needle cylinder and to the sensing means 130, 104.

A device 122 for adjusting the brightness of lamp 109, for example potentiometer, is provided and controlled by impulses produced by a photo diode 104/26 which 25 senses the additional track 110/26 which is transparent over the entire length thereof. In the event that the transparent portions of the program tracks become less transparent in the course of time, and permit the passage of less light, photo diode 104/26 responds and causes adjustment of lamp 109 so that the same amount of light passes through the transparent areas of the program tracks into the photo diodes.

The upper portion of FIG. 16 shows a circuit for supplying a constant voltage to lamp 109, the amplifiers 120 and 114, and other devices, the circuit including a three phase motor and a direct current generator indicated at 131, and a device 132 for maintaining a constant voltage.

It will be understood that each of the elements described above, or two or more together, may also find a 40 useful application in other types of selector apparatus for knitting machines differing from the types described above.

While the invention has been illustrated and described as embodied in a circular knitting machine having angularly displaceable jacks for selecting needles by selector means including an electromagnetic means and selector cams, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. Selector apparatus for circular knitting machines, comprising, in combination, rotary needle cylinder means having an axis of rotation; a cam box surrounding said needle cylinder means and having at least one circumferential jack cam track including track portions rising and falling in axial direction; a series of needles mounted on said needle cylinder means for movement in axial direction; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting

the corresponding needle; and selector means mounted on said cam box leading said rising and falling cam track portions in the direction of rotation of said needle cylinder means for selectively placing jacks in said inoperative or working positions, respectively, said selector means including biasing means for urging said jacks into said working position, a series of control elements rigidly mounted on said needle cylinder means respectively aligned in radial direction with said jacks, each control element having a normal position, and an actuated position for moving the respective jack to said inoperative position, and means for placing said control elements selectively in said normal position and in said actuated position so that non-selected jacks are moved by actuated control elements to said inoperative position and the remaining selected jacks are held by said biasing means in said working position and moved by said rising track portion of said jack cam track to said operative position to cause movement of said needles.

2. Selector apparatus according to claim 1 wherein each of said jacks has one end supported on said needle cylinder means for angular movement, and has a butt spaced from said end, said butt being located in said jack cam track in said working position and outside of said cam track in said inoperative position.

3. Selector apparatus for circular knitting machines, comprising, in combination, rotary needle cylinder means having an axis of rotation; a cam box surrounding said needle cylinder means and having at least one circumferential jack cam track including track portions rising and falling in axial direction; a series of needles mounted on said needle cylinder means for movement in axial direction; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting the corresponding needle; and selector means mounted on said cam box leading said rising and falling cam track portions in the direction of rotation of said needle cylinder means for selectively placing jacks in said inoperative or working positions, respectively, said selector means including biasing means for urging said jacks radially outwards into said working position, a series of resilient control elements mounted on said needle cylinder means respectively aligned in radial direction with said jacks located outwards of the same, each control element having a normal position, and an inwards displaced actuated position for moving the respective jack to said inoperative position, circumferential selector cam track means in said cam box having a radially outer and radially inner selector track portions for placing said control elements in said normal and actuated positions, respectively, and electromagnetic means leading said selector cam track means in the direction of rotation of said needle cylinder means and being energizable and de-energizable for placing selected control elements on said outer selector track portions, and non-selected control elements on said inner selector track portions so that non-selected jacks are moved by actuated control elements to said inoperative position and the remaining selected jacks are held by said biasing means in said working position and moved by said rising track portion of said jack cam track to said operative position to cause movement of said needles.

4. Selector apparatus according to claim 3 wherein each of said jacks has one end supported on said needle cylinder means for angular movement, and has a butt spaced from said end so that said butt is located in said cam track in said working position and outside of said cam track in said inoperative position and turns about said one end when moving between said positions thereof.

5. Selector apparatus according to claim 4, wherein said

biasing means include a series of springs, each spring being mounted on one of said jacks abutting said needle cylinder means for turning said jack into said working position.

6. Selector apparatus according to claim 3 wherein each of said control elements is a straight resilient wire extending parallel to said axis; and wherein said needle cylinder means includes a peripheral ring supporting one end of each said wire, the other end of each said wire being located in close proximity to the corresponding jack in said working position.

7. Selector apparatus according to claim 3 and including circumferential guide cam track means in said cam box having a first guide portion leading said electromagnetic means in said direction of rotation of said needle cylinder means for guiding said control elements outwards in radial direction from said normal position to a tensioned position located in the proximity of said electromagnetic means, and a second guide cam track portion following said first guide cam track portion and being located radially inward of the same, said radially outer and radially inner selector track portions having a joining edge located inward of said first guide cam track portion and outward of said second guide cam track portion for guiding control elements held in said tensioned position by said electromagnetic means onto said outer selector cam track portion, and control elements released by said electromagnetic means and sliding on said second guide cam track portion onto said inner selector track portion.

8. Selector apparatus according to claim 7 wherein said electromagnetic means has a first core magnetizable and de-magnetizable in a selected sequence corresponding to a desired knitting pattern and located in the region of said first guide cam track portion, and a permanent magnetic second core located in the region of said second guide cam track portion and of said outer selector track portion so that said first core, when magnetized holds said control elements until the same are held by said permanently magnetic second core and guided to said outer selector track portion, and when demagnetized permits the respective control elements to resiliently return to said normal position located on said second guide cam track portion for being transferred to said inner selector cam track portion.

9. Selector apparatus according to claim 7 wherein said electromagnetic means has two outer pole shoes on opposite sides of said first and second cores, said first and second cores being both permanently magnetic and having a polarity opposite to the polarity of said outer pole shoes and a winding on said first core for suppressing the permanent magnetism of said first core when energized so that the same is de-magnetized and releases the respective control element, while when said winding is not energized, said first core maintains its magnetism and guides the respective control elements to said second core whose magnetic field is not influenced by said winding.

10. Selector apparatus according to claim 9 wherein said electromagnetic means is mounted on said cam box, and wherein said pole shoes and said first and second cores of said central pole shoe have end faces extending parallel to confronting surface portions of said guide cam track means and selector cam track means and form a gap with the same, said gap being slightly wider than the thickness of said control elements, said first guide cam track portion ending substantially at the center of said end face of said first core, and said edge of said selector cam track means being located substantially at the center of the end face of said second core; and wherein said first and second cores are spaced from each other a distance smaller than the width of said control elements in the circumferential direction of movement of the same.

11. Selector apparatus for circular knitting machines, comprising, in combination, rotary needle cylinder means having an axis of rotation; a cam box surrounding said

needle cylinder means and having at least one circumferential jack cam track including track portions rising and falling in axial direction; a series of needles mounted on said needle cylinder means for movement in axial direction, said cam box having a circumferential needle cam track means including a first needle track located in a plane perpendicular to said axis of rotation, and a second needle track branching off said first needle track and including needle track portions rising and falling in axial direction and having a fixed low point; wherein said needles have butts located in said needle cam track means; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting the corresponding needle; selector means mounted on said cam box leading said rising and falling cam track portions in the direction of rotation of said needle cylinder means for selectively placing jacks in said inoperative or working positions, respectively, selected jacks moving to said working position engaging the corresponding needles for placing the same above said fixed low point in said second needle track so that thus selected needles are raised and lowered by said rising and falling needle track portions, while non-selected needles whose jacks are in said inoperative positions move along said first cam track and remain inoperative; wherein said rising needle track portion raises said needles to the tuck position; a shifting cam mounted on said cam box turnable between an operative position for guiding needles on said rising needle track portion from said tuck position to the knit position, and an inoperative position for guiding needles further in said tuck position; a stitch cam on said cam box for guiding said needles from said knit position and from said tuck position to said first needle track so that all needles finally assume the cast-off position; and locking means mounted on said cam box for movement between an inoperative position and an arresting position for holding said shifting cam in said operative position.

12. Selector apparatus for circular knitting machines, comprising, in combination, rotary needle cylinder means having an axis of rotation; a cam box surrounding said needle cylinder means and having at least one circumferential jack cam track including track portions rising and falling in axial direction; a series of needles mounted on said needle cylinder means for movement in axial direction, said cam box having a circumferential needle cam track means including a first needle track located in a plane perpendicular to said axis of rotation, and a second needle track branching off said first needle track and including needle track portions rising and falling in axial direction, said needles having butts located in said needle cam track means; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting the corresponding needle; and selector means mounted on said cam box leading said rising and falling cam track portions in the direction of rotation of said needle cylinder means for selectively placing jacks in said inoperative or working positions, respectively, selected jacks moving to said working position engaging the corresponding needles for placing the same in said second needle track so that thus selected needles are raised and lowered by said rising and falling needle track portions, while non-selected needles whose jacks are in said inoperative positions move along said first cam track and remain inoperative; wherein said rising needle track portion raises

said needles to the tuck position; a shifting cam mounted on said cam box movable between an operative position for guiding needles on said rising needle track portion from said tuck position to the knit position, and an inoperative position for guiding needles further in said tuck position; a stitch cam on said cam box for guiding said needles from said knit position and from said tuck position to said first needle track so that all needles finally assume the cast-off position; and another shifting cam mounted on said cam box substantially axially aligned with said rising track portion of said jack cam track, and being movable between an inoperative position, and an operative position bridging said first needle track leading said rising and falling cam track portions in the direction of rotation of said needle cylinder means so that said needles are guided onto said second needle track although the corresponding jacks are in said inoperative position and do not lift the corresponding needles.

13. Selector apparatus for circular knitting machines, comprising, in combination, rotary needle cylinder means having an axis of rotation; a cam box surrounding said needle cylinder means and having at least one circumferential jack cam track including track portions rising and falling in axial direction; said needle cylinder means and said cam box having a set of knitting stations adjacent in circumferential direction, each knitting station including a circumferential cam box section having a circumferential jack cam track including rising and falling track portions; a series of needles mounted on said needle cylinder means for movement in axial direction; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting the corresponding needle; selector means mounted on said cam box leading said rising and falling cam track portions in the direction of rotation of said needle cylinder means for selectively placing jacks in said inoperative or working positions, respectively, said selector means including a set of electromagnetic means respectively mounted on said cam box sections, and pattern control means for selectively energizing and de-energizing said electromagnetic means in accordance with a program, said pattern control means including a set of photo diodes whose number is the same as the number of said knitting stations, a set of circuits connecting said photo diodes with said electromagnetic means, respectively, a program tape having a set of program tracks, and means for moving said program tape between said photo diodes and a source of light so that each photo diode is controlled by light falling through a different program track, each program track including light permeable and opaque areas following each other in a selected sequence so that each of said electromagnetic means is energized under the control of an associated photo diode in accordance with light impulses received by the same depending on the sequence of light permeable and opaque areas on the respective program track, said program tape including additional tracks with light permeable and opaque areas following each other in a selected sequence, a corresponding number of additional photo diodes controlled by said additional tracks of said program tape; auxiliary devices including means for adjusting the brightness of said source of light; and circuits respectively connecting said additional photo diodes with said devices so that the same are operated in accordance with programs represented by said additional tracks of said program tape.

14. Selector apparatus according to claim 13 including optical lens means between said source of light and said program tape, said lens means including a cylindrical lens for transporting said program tape and for focusing light on a row of said areas extending transverse to the direc-

tion of said program tracks and the direction of movement of said program tape.

15. Selector apparatus according to claim 13 wherein each of said circuits includes synchronizing means for synchronizing the electric impulses produced by each of said photo diodes with the movement of said needle cylinder means and said jacks past said electromagnetic means so that each electromagnetic means is energized or de-energized at the exact moment in which it is passed by a jack.

16. Selector apparatus according to claim 15 wherein said synchronizing means includes an impulse generator located adjacent the periphery of said needle cylinder means and passed by said needles so as to produce a synchronizing impulse whenever passed by a needle, and an AND-gate receiving said synchronizing impulses and being connected with said photo diodes to receive impulses from the same, and circuit means connecting said AND-gate with the respective electromagnetic means so that the same is energized and de-energized by synchronized program controlled impulses at the exact moment when passed by a jack.

17. Selector apparatus for circular knitting machines, comprising, in combination, rotary needle cylinder means having an axis of rotation; a cam box surrounding said needle cylinder means and having at least one circumferential jack cam track including track portions rising and falling in axial direction; said needle cylinder means and said cam box having a set of knitting stations adjacent in circumferential direction, each knitting station including a circumferential cam box section having a circumferential jack cam track including rising and falling track portions; a series of needles mounted on said needle cylinder means for movement in axial direction; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting the corresponding needle; selector means mounted on said cam box leading said rising and falling cam track portions in the direction of rotation of said needle cylinder means for selectively placing jacks in said inoperative or working positions, respectively, said selector means including a set of electromagnetic means respectively mounted on said cam box sections, and pattern control means for selectively energizing and de-energizing said electromagnetic means in accordance with a program, said pattern control means including a set of photo diodes whose number is the same as the number of said knitting stations, a set of circuits connecting said photo diodes with said electromagnetic means, respectively, a program tape having a set of program tracks, and means for moving said program tape between said photo diodes and a source of light so that each photo diode is controlled by light falling through a different program track, each program track including light permeable and opaque areas following each other in a selected sequence so that each of said electromagnetic means is energized under the control of an associated photo diode in accordance with light impulses received by the same depending on the sequence of light permeable and opaque areas on the respective program track, said program tape including at least one additional program track, at least one additional photo diode for producing impulses under the control of said additional track; said selector means further including a support supporting said photo diodes, said source of light, and said means for transporting said program tape, said support having a gear, a motor having a gear meshing with said gear for displacing said support, an electromagnetic impulse generator in the proximity of the periphery of said needle cylinder means and producing control impulses when passed by a jack or needle, a phase comparison device

connected with said impulse generator and with said additional photo diode to receive the impulses produced by the same, respectively, and adapted to produce a voltage when there is a phase difference between said photo diode produced impulses and said impulse generator produced impulses, and means for supplying said voltage to said motor so that the position of said support is adjusted to synchronize the impulses produced by said photo diodes with the passage of a jack or needle by the respective electromagnetic means.

18. Selector apparatus according to claim 17 wherein said means for transporting said program tape include a cylindrical lens transporting said program tape and focusing light on a row of said areas transverse to said program tracks and the direction of movement of said program tape, said row of areas being sensed by said photo diodes and by said additional photo diodes; wherein said gear has its axis of rotation coinciding with the axis of said cylindrical lens; and means for connecting said needle cylinder means with said cylindrical transporting lens for driving the latter from said needle cylinder means.

19. Selector apparatus for circular knitting machines, comprising, in combination, rotary needle cylinder means having an axis of rotation; a cam box surrounding said needle cylinder means and having at least one circumferential jack cam track including track portions rising and falling in axial direction; said needle cylinder means and said cam box having a set of knitting stations adjacent in circumferential direction, each knitting station including a circumferential cam box section having a circumferential jack cam track including rising and falling track portions; a series of needles mounted on said needle cylinder means for movement in axial direction; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting the corresponding needle; and selector means mounted on said cam box leading said rising and falling cam track portions in the direction of rotation of said needle cylinder means for selectively placing jacks in said inoperative or working positions, respectively, said selector means including a set of electromagnetic means respectively mounted on said cam box sections, and pattern control means for selectively energizing and de-energizing said electromagnetic means in accordance with a program, said pattern control means including a set of photo diodes whose number is the same as the number of said knitting stations, a set of circuits connecting said photo diodes with said electromagnetic means, respectively, a program tape having a set of program tracks, and means for moving said program tape between said photo diodes and a source of light so that each photo diode is controlled by light falling through a different program track, each program track including light permeable and opaque areas following each other in a selected sequence so that each of said electromagnetic means is energized under the control of an associated photo diode in accordance with light impulses received by the same depending on the sequence of light permeable and opaque areas on the respective program track, said program tape including an additional track which is light permeable along the entire length thereof; said selector means including an additional photo diode for receiving light from said additional track and responding to light variations of said source of light, and means for adjusting the brightness of said source of light controlled by impulses produced by said additional photo diode to maintain said source of light in a condition emitting light of desired intensity.

20. Selector apparatus for circular knitting machines, comprising, in combination, rotary needle cylinder means having an axis of rotation; a cam box surrounding said

needle cylinder means and having at least one circumferential jack cam track including track portions rising and falling in axial direction; a series of needles mounted on said needle cylinder means for movement in axial direction; a shifting cam mounted on said cam box for turning movement between an inoperative position for guiding needles to a tuck position, and an operative position for guiding needles to a knit position; a locking means mounted on said cam box for movement between an inoperative position and an arresting position for holding said shifting cam in said operative position; a series of jacks registering with said needle means, respectively, each jack being mounted on said needle cylinder means for movement in axial direction, and also for movement in radial direction between an inoperative position and a working position engaging said jack cam track so as to be moved by said rising and falling track portions to and from an operative position for lifting the corresponding needle; and selector means mounted on said cam box leading said rising and falling cam track portions in the direction of rotation of said needle cylinder means for selectively placing jacks in said inoperative or working positions, respectively.
